(57) **CLAIM**

The ornamental design for a hook, as shown and described.

DESCRIPTION

FIG. 1 is a perspective view of the front, top and right side of a hook showing my new design;

FIG. 2 is a front view thereof;

FIG. 3 is a rear view thereof;

FIG. 4 is a top plan view thereof;

FIG. 5 is a bottom view thereof;

FIG. 6 is a left side view thereof;

FIG. 7 is a right side view thereof;

FIG. 8 is a front view of the male part thereof;

FIG. 9 is a rear view of the male part thereof;

FIG. 10 is a top plan view of the male part thereof;

FIG. 11 is a bottom view of the male part thereof;

FIG. 12 is a left side view of the male part thereof;

FIG. 13 is a right side view of the male part thereof;

FIG. 14 is a front view of the female part thereof;

FIG. 15 is a rear view of the female part thereof;

FIG. 16 is a top plan view of the female part thereof;

FIG. 17 is a bottom view of the female part thereof;

FIG. 18 is a left side view of the female part thereof; and,

FIG. 19 is a right side view of the female part thereof.

The elements of the hook are shown separate for ease and clarity of illustration.
